UNITED STATES PATENT OFFICE.

AUGUST KUZNIK, OF CLEVELAND, OHIO, ASSIGNOR OF THREE-FOURTHS TO ANDREW LILLIE, OF CLEVELAND, OHIO.

PROCESS OF MAKING MOLDS.

1,347,168.

Specification of Letters Patent. Patented July 20, 1920.

Application filed July 11, 1919. Serial No. 310,148.

To all whom it may concern:

Be it known that I, AUGUST KUZNIK, a citizen of the United States, residing at Cleveland, in the county of Cuyahoga and 5 State of Ohio, have invented a certain new and useful Improvement in Processes of Making Molds, of which the following is a full, clear, and exact description, reference being had to the accompanying drawings. 10 This invention relates to molds and has for its general object to insure the production of castings which are free from sand and other impurities. I secure this general object in and through the manner of forming 15 a mold shown in the drawings forming part hereof, wherein Figure 1 represents a central vertical sectional view through such mold; Fig. 2 a sectional view corresponding to the line 2—2 of Fig. 1, the position of the 20 pouring gate or opening in the cope being indicated in dot-and-dash lines; Fig. 3 a side elevation of a pattern employed in connection with the making of the mold and in the practice of my process; and Fig. 4 a 25 detail in perspective of a core member employed in the making of such mold and the practice of such process.

Describing the parts by reference characters, 1 denotes the drag and 2 the cope of 30 a mold of ordinary construction. In casting articles of various shapes, it is extremely desirable to keep the quality of the iron as high as possible and, with this object in view, I preferably provide in the mold a 35 chamber for the reception of the molten metal from which it is distributed to the mold cavity proper by means of a trapped outlet, thus insuring the presence at all times of a body of molten metal between the pouring point and the mold cavity, whereby any 40 sand or other impurities will be prevented from passing into the said cavity. In Fig. 1, I have shown a mold cavity at 3 communicating by a suitable channel 4 and a trapped 45 outlet 5, ^{5a} with the bottom of an intermediate chamber 6.

For the purpose of forming the intermediate chamber and the trapped outlet therefrom, I prefer to employ a pattern such 50 as shown in Fig. 3. This pattern comprises an upper oval section 7 and a lower oval section 8, the lower section being provided with a lateral projection 9 and a rounded rib 10 projecting from the middle of the 55 rear of such projection and extending lon-

gitudinally of such projection as well as therebeneath as shown at 11. In forming a mold by the use of the pattern 7—11, the pattern members will be supported in the mold box in the usual manner with the top 60 of the section 8 and the top of the projection 9 and rib 10 at or near the top of the drag. The pattern will also be supported in the mold box in the usual manner. As shown herein, the top of the pattern has 65 been supported substantially even with the top of the drag, but this is merely for purpose of illustration. The sand then having been rammed, the cope is lifted from the drag, the patterns removed, and an opening 70 12 is provided, which preferably communicates with the upper portion of the chamber 6 which is formed by the removal of the patterns 7—11. A gate or filling opening 13 is also provided in the sand and is shown 75 in the cope section, the bottom of said opening communicating with the central portion of the chamber 6 at one side and tangentially thereof, so that a whirling motion will be imparted to the molten metal entering the 80 same. There will then be formed in the sand a chamber 6 the bottom section of which is laterally enlarged and projecting 85 toward the mold cavity 3, but spaced therefrom. A core 14 which is of the same shape 90 as the lateral projection 9, with the exception that it is provided with a central vertical half round channel 15 and a bottom half round channel 16, is then applied to and within the cavity produced by the projection 9, with the result that, from the bottom 95 of the lower portion of the chamber 6, there extends a circular channel 5 which merges with an upwardly inclined circular channel 5^a leading, with the parts arranged as described, to the top of the sand in the drag section of the mold. The core 14 is made of core sand, the channel 4 is then formed in the sand in the top of the drag section and provides a continuous trapped outlet 100 from the bottom of the chamber 6 to the top of the mold cavity 3.

In forming a mold the operator pours the molten metal into the gate or opening 13, and when this metal rises above the 105 bottom of the channel 4, it may then enter the mold cavity. By this mode of forming the mold, the mold chamber will be filled while maintaining at all times a body of molten metal in the chamber 6. Any sand, 110

cinder, or other sediment which is of less gravity than the molten iron will evidently rise to the top of the iron in the chamber 6 and overflow from the outlet gate or opening 12. Because of the manner of introduction, the metal entering the chamber 6 is given a whirling motion similar to that imparted by stirring with a ladle, and a certain proportion of the sediment will adhere 10 to the sand constituting the wall thereof. By introducing the metal into the chamber 6 below the top of the latter, the separation of the coke and sediment upwardly is facilitated. After the pouring operation, the 15 metal in said chamber and in the trapped outlet may be removed and remelted. It will be noted that the chamber 6 is egg-shaped and that the trapped outlet leads from the lowest point in the concave bottom 20 thereof. With this shape of chamber, some whirling of the metal poured thereinto will occur, even though no special provision be made for introducing the metal tangentially of the chamber. Connecting the trapped 25 outlet with the bottom of the chamber prevents the passage of any material amount of coke or other sediment into the molding cavity; for, as soon as the horizontal lower portion of the trapped outlet is filled with 30 the metal, the coke or other sediment is whirled outwardly by centrifugal action and rises into the upper portion thereof, and, if present in large proportion, may even enter the outlet 12.

35. Having thus described my invention, what I claim is:

1. A mold having a molding cavity, a separating chamber provided with a concave bottom, a trapped outlet leading from

the central portion of such bottom to the 40 molding cavity, and a pouring gate for delivering molten metal to said chamber tangentially thereof.

2. A mold having a molding cavity and a separating chamber which is substantially 45 circular in cross section and having a concave top and bottom, a trapped outlet communicating with the central portion of the bottom of such chamber and extending to the molding cavity, means for introducing 50 molten metal into said chamber below the top thereof and for imparting a whirling motion to such metal, and an outlet for sediment extending from the upper portion of said chamber.

3. A mold having a molding cavity, an egg-shaped separating chamber, a trapped outlet leading from the central portion of the bottom of said chamber to the molding cavity, an outlet for sediment extending 60 from the top of said chamber, and a pouring gate communicating with said chamber.

4. A mold having a molding cavity, an egg-shaped separating chamber, a core forming part of the lower wall of said 65 chamber and provided with a groove forming part of a trapped outlet channel leading from the central portion of the bottom of said chamber to said cavity, an outlet for sediment extending from the upper portion 70 of said chamber, and a pouring gate arranged to deliver molten metal tangentially of said chamber and between the top and the bottom thereof.

In testimony whereof I hereunto affix my 75 signature.

AUGUST KUZNIK.
